[57] CLAIM

The ornamental design for a lawn swing, as shown and described.

DESCRIPTION

FIG. 1 is a perspective drawing of our lawn swing and wherein a mosquito netting drape is shown attached to the swing in a partially opened condition;

FIG. 2 is a perspective drawing showing a front elevation and partial top view of our lawn swing, the rear elevation view being a mirror image;

FIG. 3 is a perspective drawing showing a right side and partial top view thereof, the left side view being a mirror image;

FIG. 4 is a top plan view thereof; and,

FIG. 5 is a bottom plan view thereof.
